UNITED STATES PATENT OFFICE

FRIDOLIN POLZER, OF SOUTH NORWALK, CONNECTICUT, ASSIGNOR TO THE E. H. HOTCHKISS COMPANY, OF NORWALK, CONNECTICUT, A CORPORATION OF CONNECTICUT

TACKER

Application filed July 28, 1930. Serial No. 471,353.

This invention relates to new and useful improvements in tacking machines such as are used for securing direction or other labels to shipping boxes, and like uses.

6 An object of the invention is to provide a machine for the purpose stated which machine is operable in the fashion of a hammer, the machine carrying a strip of staples which are automatically fed forward to be used 10 one at a time, each time the machine is forcefully brought into engagement with the object into which it is desired to drive the staple or tack.

15 Another object of the invention is to provide a tacking machine of the character stated the same being so constructed that after a slight adjustment, the machine may be used as an ordinary hammer.

20 Other objects and advantages will become apparent from a consideration of the following detailed description taken in connection with the accompanying drawing showing one embodiment of the invention. While the invention is shown and will be described in detail, it is to be understood that changes in construction, combination and arrangement of parts may be made without departing from the spirit of the invention or the scope of the appended claims.

25 In the drawing:

Fig. 1 is a side elevational view of the complete machine, parts being broken away to more clearly illustrate the details of construction and the machine being shown in the act of driving a staple.

30 Fig. 2 is an end view of the complete machine looking from the left of Fig. 1.

Fig. 3 is a view taken at right angles to Fig. 2, the handle portion being omitted and showing the plunger in elevated position.

Fig. 4 is a plan view of the hammer head:

posed thereon, the latter being used one at a time to be driven by the plunger, and the strip being fed forwardly along the guide bar by means of a follower 15. The staples are preferably of the substantially U-shaped type.

55 Follower 15 is substantially U-shaped in section and straddles the guide bar 13 whereby its front end will be in engagement with the last staple of the strip, the strip also being U-shaped and straddling the guide bar. In its upper surface the follower 15 is provided with a small elongated opening 16 through which is hooked a stud 17 carried by a button or finger piece 18. To the piece 18 is secured one end of a flat spring 19 the other end of which is secured to a cross member or rivet 20 in the housing, the spring being wound about the rivet 20 as clearly shown in the dotted lines in Fig. 1. As will be understood the tendency of the spring is to wind itself up and due to this tendency the follower is drawn along the guide bar 13 feeding the strip 14 forwardly as it is used up to bring the individual staples successively one at a time to driving position under the plunger.

70 A stem 21 carrying a plunger 22 has a hammer head 23 secured to its upper end by any suitable means as by pin 24. Within the housing 10, the stem 21 is hollow and disposed within the stem is a coil spring 25 which with a flat spring 26 secured to the shank at 27 and engaging the under side of the hammer head as at 28, serves to normally maintain the hammer head, stem 21 and plunger 22 in elevated position as shown in Figs. 2 and 3. Either one of the springs may be dispensed with if desired but two springs are preferably used to insure proper operation.

75 With the mechanism above described the

action of the springs to force the plunger 22 to engage the first staple on the strip 14 carrying said staple downwardly in the guide way between the portion 29 and the forward 5 end of the shank 11 to embed the same in the object suggested in Fig. 1 and designated 30 such as a shipping box and the tag or label to be secured thereto indicated at 30^a. In other words every blow will automatically set 10 a staple through operation of the plunger by the momentum of the weighted head 23, and no hand or other operation of the plunger is required.

It is sometimes desirable to use the machine 15 or tool as an ordinary hammer and to this end means are provided whereby on a slight adjustment being made the device may be used as an ordinary hammer, the head 23 to this end being provided with a striking surface 20 31, and if desired may also have claws 31^a. To the head 23, forwardly of the housing 10, there is secured a depending member 32 having a slot 33. Screw threaded, forced, or otherwise secured to the forward face of 25 the housing 10 is a stud 34. This stud 34 passes through the slot 33 in the member 32, and pivotally secured to the outer end of the stud as at 35 is a lug or pawl 36.

Pawl 36 adjacent its pivoted end is provided with oppositely disposed notches 37 30 adapted in different positions of the pawl to be engaged by a spring pressed ball 38 arranged within the stud 34. As suggested in Fig. 1 the pawl 36 has two positions, one being 35 against the outer face of the member 32 as shown in full lines and the other being within the slot 33 with the end 39 of the pawl in engagement with the lower end 33^a of the slot 33 in the member 32. In this latter position 40 wherein the pawl is shown in dotted lines, the pawl will act to maintain the hammer head 23 in its depressed or lowermost position as shown in Fig. 1. When the parts are in this position the inner end of the stem 45 21 will be abutting a stop or limiting means or block 40, and further inward movement of the stem will be prevented by this stop means.

When the hammer head 23 is held depressed 50 against the action of the springs 25 and 26 the plunger 22 is of course, also, held depressed and the machine may be used as a hammer either to drive tacks or other uses for which a hammer is ordinarily employed. 55 The claw portion 31^a may have one claw longer than the other as shown so that if the staple to be drawn happens to be too narrow to receive both claws one only, the longer one, may be inserted under the bar of the staple 60 to remove it. The claw portion may be used for removing tacks, nails and the like the same as the usual claw on a hammer. Since the plunger 22 is held depressed it will prevent additional staples of the strip 14 from 65 being fed forward into position for use and

it will not reciprocate up and downwardly to eject them from the machine. Also, it is to be noted that the end of the stem 21 has entered the housing 10 as far as possible and being held in this position with the end of its stem 70 in engagement with the stop 40 a rigid hammer construction is provided.

To have the device again act as a tacking machine for automatically driving staples, it is but necessary to swing the pawl 36 from the dotted line position of Fig. 1 to the full line position thereof. To again change the device into a hammer it is but necessary to hold the parts depressed and swing the pawl 75 36 from the full line position of Fig. 1 to the dotted line position thereof with its free end against the shoulder 33^a.

Having thus set forth the nature of my invention, what I claim is:

1. In a tacking machine, a shank, a handle 80 at one end of the shank, a housing at the other end of the shank, a guide bar within the shank and adapted to have a strip of staples supported thereon, means for feeding the staples along the guide bar to the housing, a stem extending from the housing, a weight secured to the outer end of the stem, a plunger secured to the stem, spring means for normally maintaining the stem weight and plunger elevated, a stop means to be engaged by the stem to limit the movement of the stem 85 into the housing, and said weight adapted to overcome the action of the spring means and depress the plunger to drive a staple when the machine is forcefully brought into 90 contact with the object to be tacked.

2. In a tacking machine including a housing, a stem extending from the housing, a plunger carried by the stem, a weight having a striking surface secured to the end of the stem extending from the housing, a stop for limiting the movement of the stem into the housing, spring means for normally maintaining the stem, plunger and weight elevated, said weight adapted to overcome the action of the spring means and depress the plunger to drive a staple on the machine being forcefully brought into contact with the object to be tacked, and means to lock the weight and plunger in depressed position 100 with the stem against the stop whereby the machine may be used as a hammer, the weight providing the hammer head.

3. In a tacking machine including a housing, a stem extending from the housing, a plunger carried by the stem, a weight secured to the extending end of the stem and provided with a striking surface, a spring means for normally maintaining the stem, plunger and weight elevated, a member carried by the weight and disposed at the forward side of the housing, said weight adapted to overcome the action of the spring means and depress the plunger to drive a staple on the machine being forcefully brought into contact 110

with the object to be tacked, and means on the head for engaging the member carried by the weight for locking said member against movement in one direction with the weight in depressed position, whereby the weight may be used as a hammer head.

4. In a tacking machine including a housing, a stem extending from the housing, a plunger carried by the stem, a weight secured to the extending end of the stem provided with a striking surface, a spring means for normally maintaining the stem, plunger and weight elevated, a member carried by the weight and disposed at one side of the housing, said weight adapted to overcome the action of the spring means and depress the plunger to drive a staple on the machine being forcefully brought into contact with the object to be tacked, said member carried by the weight having a slot, and means on the head for engaging one end wall of the slot in said member to lock said member against movement in one direction with the weight in a depressed position, whereby the weight may be used as a hammer head.

5. In a tacking machine including a housing, a stem extending from the housing, a plunger carried by the stem, a weight secured to the extending end of the stem, a spring means for normally maintaining the stem, plunger and weight elevated, a member carried by the weight and disposed at one side of the housing, said weight adapted to overcome the action of the spring means and depress the plunger to drive a staple on the machine being forcefully brought into contact with the object to be tacked, said member carried by the weight having a slot, means on the housing extending through the slot in said member, and means pivoted to said means on the housing and adapted to be moved into one of two positions, and said means in one of its positions engaging one end wall of the slot in said member to lock the member against movement in one direction with the weight in a depressed position whereby the weight may be used as a hammer head.

6. In a tacking machine, a housing, a handle by which the housing may be used to strike a blow, a movable plunger in the housing, a weight connected to the plunger having a striking surface, a spring tending to hold the plunger and weight in retracted position, said weight being adapted through momentum created by said blow to advance the plunger to drive a staple, and manually operable means to lock the weight and plunger against movement to permit use of the device as a hammer.

7. In a tacking machine including a housing, movable means including a stem extending from the housing, a plunger carried by the stem, a weight secured to the stem and provided with a striking surface, spring means for normally maintaining the stem,

plunger and weight elevated, said weight adapted to overcome the action of the spring means and depress the plunger to drive a staple when the machine is forcefully brought into contact with the object to be tacked, and means to lock the stem against movement in one direction with the weight in depressed position whereby the weight may be used as a hammer head, said means including a pivoted pawl carried by the housing and adapted to be moved to engage a part of the moving means.

8. In a tacking machine including a housing means, means movable relative to the housing and including a stem extending from the housing, a plunger carried by the stem, a weight secured to the extending end of the stem and provided with a striking surface, spring means for normally maintaining the stem, plunger and weight elevated, said weight adapted to overcome the action of the spring means and depress the plunger to drive a staple on the machine being forcefully brought into contact with the object to be tacked, and means for locking the movable means against movement to elevated position relative to the housing with the weight in depressed position whereby the weight may be used as a hammer head, said locking means including a pawl on one of the first two mentioned means and adapted to enter a recess in the other of the first two mentioned means.

In testimony whereof I affix my signature.
